UNITED STATES PATENT OFFICE.

RICHARD HENRY QUINE, OF MANCHESTER, ENGLAND.

BATH AND STAND FOR THE SAME.

No. 900,586.

Specification of Letters Patent.

Patented Oct. 6, 1908.

Application filed January 15, 1908. Serial No. 410,959.

To all whom it may concern:

Be it known that I, RICHARD HENRY QUINE, a subject of Great Britain, residing at Sandy Grove House, Eccles Old Road, 5 Pendleton, Manchester, in the county of Lancaster, England, surgeon, have invented new and useful Improvements in Baths and Stands for the Same, of which the following is a specification.

10 My invention relates to portable baths and stands for the same and has for its object to produce a new type of bath on which adult users may sit during the washing, or other process performed when astride of same.

15 The bath itself is so constructed that a minimum quantity of contained water will serve to effectively cleanse the body, the construction being also such that the bath can be straddled with comfort, the supporting 20 slopes to be later described serving to return water splashed or running off the body back to the bath where it again collects.

The bath is intended to be supported on a collapsible, or other stand, at such a height 25 as not to exceed the distance from floor to knee-joint so that a user's comfort is not sacrificed and the body is well disposed or displayed for cleansing.

30 The complete device is admirably adapted for cleansing the lower portions of the trunk; or for use when injecting cleansing medications, or using lotions. Likewise the bath serves well for washing infants or young children when actually seated therein.

35 The drawings attached show a good form the new portable bath and stand may assume, and also indicate various obvious modifications or variations.

Figure 1 is a side elevation of the new bath 40 and stand complete, with the handles elevated ready for lifting. Fig. 2 shows a longitudinal section of the bath. Fig. 3 shows an end elevation of Fig. 1. Fig. 4 is a plan of the bath seen in Fig. 1, but with the handles 45 turned down. Fig. 5 shows a transverse section of the bath, but on a modified form of stand. Fig. 6 indicates a modification in the cross-section of the bath where horizontal ledges are used with a rounded pocket or 50 well. Fig. 7 shows on a smaller scale another modified form of bath without special ledges for a utensil, but still with a pocket or well. Fig. 8 is a further modification where an angular pocket or well is used. Fig. 9 55 shows a variation in design from Fig. 8. Fig.

10 shows a further variation in design from Figs. 8 and 9.

In baths such as are contemplated by my invention, I use a vessel *a* which is preferably elongated or oblong in the direction of its 60 length, and in all cases has a broad rim or ledge running longitudinally on either side which ledges or rims *a'*, *a'* slope inwards and downwards. In other words, these ledges or rims, descend from the extreme lip or edge 65 until they join the main body of the bath at the points *a²*, *a²*, as the drawings clearly show. These inward slopes are employed for a four fold purpose, that is with the object of supporting the bath on the stand, providing comfortable seating surfaces, displaying for access portions of the body for cleansing and treatment, and for returning any water, splashed by the user, back to the body 70 of the bath. The bath body is suitably dished out to form a cavity or washing space marked *a³* running longitudinally. The width of the bath is of such dimensions as to permit an adult user to straddle the same with comfort and to squat on the extended 75 ledges or rims *a'*, *a'*, which being inwardly inclined, are, owing to anatomical reasons, naturally comfortable as a seat. When astride of the bath, a user has free access to the contents of the bath, both at the front 80 and rear, and can readily get at the lower parts of the trunk and also to the back and chest. The dished out or lower portion of the bath *a³*, which gives area, is made with a longitudinal pocket or well *a⁴* with the express object of enabling washing to be performed with a minimum of water, the pocket or well *a⁴*, giving depth, from which an adequate quantity of water can be taken-up by 85 a sponge or otherwise and used to sluice or 90 wash the body.

The preferred forms of bath have sloped or straight ledges *a⁵*, *a⁵*, and the pocket or well *a⁴* is most conveniently intermediate thereof, such ledges providing a normal bottom upon 100 which an infant immersed in the bath may rest, the channel or way, opened-up by the pocket or well *a⁴*, allowing access for the hand and thus greatly facilitating the thorough washing of young children. The 105 ledges *a⁵*, *a⁵*, when douching or treating the body, also serve to support any utensil (such as *f*, Fig. 6) acting as a receptacle. One or both ends of the bath is formed with a spout *a⁶* which serves to prevent slop or mess in 110

pouring out the contents. The bath is provided with removable or other handles *b*, the hooked ends of which may for example engage staples or eyes *b'*, *b'* attached to the bath body. These handles are very convenient when lifting the bath about, or to support the same when the contents are being emptied, in which case they occupy somewhat the position shown in Fig. 1. When turned 10 down, as in Fig. 4, then the handles *b* may be used to carry a soap or other receptacle *c* and towel *d* (see Fig. 4).

The new bath is intended to be supported on a stand *e* of a light description and furnished with bearers *e'*, *e'*, upon which the ledges or rims *a'*, *a'*, rest. The height of the stand preferably does not exceed the distance from floor to knee-joint in an average adult, whereby in the seated or straddling 15 position the feet can still rest on the floor, thus adding to the comfort of the user.

The stand *e* is preferably a collapsible structure, and, in Figs. 1 and 3, is shown consisting of legs *e²* tied together by rods *e³* pivoted at the points *e⁴*, *e⁴* and jointed at *e⁴*. The tie-rods *e⁵* can be detached from the fixing screws at *e⁵*, *e⁵*, and the legs *e²* from the bearers *e'*, *e'*, to permit of the entire stand or support being folded up into small compass. When so folded up, the entire stand *e*, with the handles *b*, may be packed into the interior of the bath. Thus the entire device can be stowed away in small compass and is consequently useful for travelers. 20 The stand need not necessarily be a collapsible one, and in Fig. 5 a non-collapsible stand *e* is shown.

In Figs. 1 to 5, and also in Fig. 6 lateral ledges *a⁵*, *a⁵* are shown, but these may be dispensed with and the inwardly sloping rims *a'*, *a'* and the well or pocket only retained, as is shown by the examples Figs. 40 7 to 10, and in such cases should a utensil be

used it will be supported by the gradually approaching walls of the pocket *a⁴*.

The bath may be stamped, pressed, molded, or otherwise produced, and be either of metal, earthenware or other suitable material.

I declare that what I claim is

1. In portable bath contrivances, a bath having longitudinal inwardly and downwardly slipping rims, a cavity in said bath, ledges at the base of said cavity, and a well, and a stand for supporting said bath, as 55 herein described.

2. A portable bath consisting of a longitudinal tank, longitudinal inwardly and downwardly sloping rims, a main cavity, ledges therein, and a well, substantially as 60 described.

3. A portable bath consisting of a longitudinal tank, longitudinal inwardly and downwardly sloping rims, a main tank, ledges, and an intermediate well, and detachable handles for the bath, substantially 65 as described.

4. A portable bath consisting of a longitudinal tank, longitudinal inwardly and downwardly slipping rims, a main tank, 70 ledges, and an intermediate well, and a pouring spout, substantially as described.

5. A portable bath contrivance consisting of a longitudinal tank, downwardly and inwardly sloping rims, a main cavity in the 75 tank, a well, ledges connecting the walls forming the well with the walls forming the cavity and a collapsible stand having legs.

In testimony whereof I have signed my name to this specification in the presence of 80 two subscribing witnesses.

RICHARD HENRY QUINE.

Witnesses:

RICHARD IBBERSON,
ALFRED YATES.
